REFRIGERATION

Alonzo W. Ruff, York, Pa., assignor to York Ice Machinery Corporation, York, Pa., a corporation of Delaware

Application May 8, 1931, Serial No. 536,028

9 Claims. (Cl. 62—91.5)

This invention pertains to refrigeration, and more particularly to a method of and means for utilizing solid carbon dioxide in refrigerating units.

5 Ordinarily the extremely low temperature of solid CO₂ makes its use impracticable for direct cooling of meats and other foodstuffs. Even in ice cream cabinets the ice cream becomes very hard, making it difficult to dispense the frozen 10 cream without first allowing an appreciable rise in its temperature.

It has heretofore been proposed to employ a secondary convector liquid or gas to act as an intermediary refrigerant between a primary refrigerant having very low temperature characteristics and the articles to be cooled. While the interposition of a secondary refrigerant avoids heat transfer at extremely low temperatures, efforts to control the temperatures in the refrigerating chamber have met with only partial success. Since it is desirable to maintain the temperature in the refrigerator fairly uniform, the temperature control of the evaporating chamber containing the secondary refrigerant within close 25 limits is important. It is equally important that a secondary refrigerant capable of close regulation be employed.

The present invention has for one of its objects the control of the temperature of the refrigerating chamber, the specific means adopted in the present instance being a thermostatically actuated valve on the vapor side of an evaporator coil containing the secondary refrigerant. A rise in temperature within the compartment to be refrigerated results in the opening of the valve to permit evaporation of the secondary refrigerant. Conversely, the valve actuator responds to a drop in temperature in the compartment to close the valve and interrupt evaporation.

40 Another object of the invention is to provide a combined container and condenser, the solid CO₂ being deposited in the container in which it liquefies and the condenser being so disposed in the container that maximum heat transfer between the liquid CO₂ and the secondary refrigerant is effected.

A further object of the invention is to effect an economy in the use of the primary refrigerant by utilizing cold gas evolved therefrom to supplement the secondary refrigerant and supply other accessories, such as carbonated water faucets, with CO₂ gas where the latter is employed as the primary refrigerant.

55 Reference to the appended drawings will en-

able those skilled in the art clearly to understand the mode of operation of apparatus embodying the principles of the invention.

In the drawings:

Fig. 1 is a schematic arrangement of the constituent parts of the apparatus, and although their disposition in a refrigerating chamber is not precisely as shown, it is to be understood that the evaporator coil and thermostat are so placed in the chamber that effective regulation 10 and desirable temperature conditions are maintained;

Fig. 2 is an elevation, partly in section, of the jacketed holder for the primary refrigerant, the space between the walls serving as a condenser 15 for the secondary refrigerant;

Fig. 3 is a top plan view of an ice cream cabinet in which a refrigeration system similar to that illustrated in Fig. 1 is employed;

Fig. 4 is a front elevation, partly in section, of the cabinet shown in Fig. 3; and

Fig. 5 is a sectional view of the containers for the CO₂.

In the form of the invention illustrated in Figs. 1 and 2, the primary refrigerant is solid CO₂ having initially a temperature of approximately -109° F. at atmospheric pressure, while the secondary refrigerant circulating in a closed cycle, which includes an evaporator coil within the space to be refrigerated, is ammonia or methyl chloride. There are other secondary refrigerants, however, which are suitable for use in the present system.

The solid CO₂ is placed in a jacketed container 11, the details of which are illustrated in Fig. 2. 35 This container comprises an inner drum 12 surrounded by a jacket 13 spaced therefrom, the inner drum being supported by a leg 14. The container is suitably heat insulated, as indicated at 15, and a cover 10 adapted to be bolted or otherwise secured to the drum forms a tight closure therefor.

An outlet for the CO₂ gas evolved in the drum is shown at 16, and this outlet connects with a discharge pipe 17 having therein a pressure regulator 18. The pressure regulator is preferably set at 100 pounds gage, or thereabouts, so that the CO₂ within the drum will either sublime or liquefy. In either case this pressure will maintain a temperature within the drum of approximately -50° F.

The chamber formed between the drum and jacket, indicated at 19, is connected with an evaporator 20 in a refrigerator chamber 21 through pipes 22, 23, nipples 24, 25 on the jacket being 55

provided for this purpose. As shown in Fig. 1, the lowermost coil of the evaporator is disposed at a lower level than that of chamber 19.

Ammonia, methyl chloride or other suitable secondary refrigerant, is contained in chamber 19 and in the lower coils of the evaporator, the pressure of the secondary refrigerant being fixed when the evaporator is originally charged to maintain a temperature of approximately -25° F. in the evaporator and about 0° F. in chamber 21. A suitable valved inlet 26 is provided to fill the circuit with the secondary refrigerant.

It will be understood that the secondary refrigerant in the evaporator will be vaporized when subjected to the relatively high temperature of the refrigerator chamber and pass in a gaseous state to the chamber 19. As the gaseous secondary refrigerant comes in contact with the cold surface of drum 12 it will be condensed. The liquefied secondary refrigerant then flows by gravity through pipe 22 and liquid trap 30 to the lower coil of the evaporator in which it is again vaporized. The secondary refrigerant circuit thus acts automatically to effect heat transfer between the evaporator and the refrigerating chamber on the one hand, and between the condenser chamber 19 and the carbon dioxide on the other.

The means for regulating the temperature of the evaporator comprises, in the present instance, an electrically actuated valve 27 disposed in the pipe connection 23, i. e., the return line, between the evaporator and the condensing chamber 19. The electrical actuator may be, and preferably is, a solenoid adapted to be energized to open or close valve 27 upon closing of a thermostatically controlled switch 28 responsive to the temperature of the refrigerator chamber 21.

A suitable source of current, as a battery 29, supplies the necessary energy for actuating the valve. So long as the temperature of the refrigerating chamber is below a predetermined value, the valve 27 remains closed to retard evaporation of the liquefied secondary refrigerant in the evaporator, the pressure of the vaporized secondary refrigerant backing up the liquid refrigerant into the condenser chamber 19, reducing the effective area of the evaporator, thus retarding evaporation. When, however, the temperature rises sufficiently to operate the thermostatically controlled switch 28, the valve will be opened to permit more rapid evaporation of the secondary refrigerant, incidentally increasing the rate of heat exchange between the CO_2 and the secondary refrigerant. Due to the limited space in the condenser, it is inadvisable to load the circuit with more refrigerant in its liquid form than can be contained in the condenser chamber during this last-mentioned stage of operation.

For the purpose of properly observing pressure and temperature conditions in the secondary circuit, there are provided a pressure gage 31 and thermometer well 32 in the pipes 23 and 22, respectively. There is also provided a lamp 39 in the solenoid circuit to indicate whether the valve is opened or closed. This latter signal may be used as indication of the supply of CO_2 in the container, it being obvious that abnormally long periods of evaporation indicate the necessity for replenishment of the charge of CO_2 .

It is customary in refrigerating installations employing solid CO_2 to permit the gas evolved during sublimation to pass to the atmosphere. Suitable means are provided by the present invention for utilizing the gas thus wasted before its passage to the outer air.

As shown in Fig. 1, pipe 17 has an extension 33 directed to enter the refrigerator 21 and lie in proximity to the evaporator 20, the waste gas passing through this extension before being vented to the atmosphere. A branch pipe 34 is also connected to pipe 17 as well as to a mixing valve or faucet 35 of the type common to soda fountains, so that the CO_2 gas may be used for carbonating water. A check valve 36 to prevent backflow of gas from the extension when the drum is open for loading is also provided; likewise, a pressure gage 37 and valved outlet 38 are connected to pipe 17.

The operation will be apparent from the previously described arrangement of the apparatus and the functions of its various elements. The drum is first loaded with solid CO_2 , usually supplied as compressed blocks of snow-like carbon dioxide. The blocks are, of course, extremely cold and tend to sublime at normal atmospheric temperatures and pressures. The drum is, therefore, supplied with an air-tight cover and provided with gaskets to prevent escape of the CO_2 gas except through pipe 17.

As stated hereinbefore, the regulator 18 maintains a pressure in the drum corresponding with a liquid temperature of -50° F. for CO_2 . The secondary refrigerant in the evaporator 20 vaporizes to produce a temperature therein of about -25° F. and in so doing extracts heat from the refrigerating chamber. As the vaporized secondary refrigerant contacts the surface of the CO_2 drum, it is condensed thereon and flows in liquid form either by gravity or by suitable pumping means back to the evaporator. Except when the flow of secondary refrigerant is interrupted by thermostatic actuation of valve 27, the refrigerating cycle is continuous and automatic.

In Figs. 3, 4 and 5, there is illustrated a practical application of the invention to an ice cream cabinet. Similar reference characters are employed wherever the parts correspond with those shown in Fig. 1. The CO_2 containers 12, 12', of which there are two connected by pipes 41, 42, at the top and bottom respectively, are each provided with a closure 10. Each closure is elliptical and cooperates with a similarly shaped opening 43 in the top of the container. The closures and openings may be square or any other shape to permit insertion of the closure so that it will seal the container on the inner side of the top thereof. The closures are clamped in position to seal the container by yokes 44.

As distinguished from the jacket surrounding the container in Fig. 1, the condenser chamber shown in Figs. 4 and 5 is a U-shaped channel-like chamber 45 welded on the inner walls of the container some distance above the bottom thereof and connected by upper and lower pipes 46, 47. Connections 24, 25 provide for communication between the condenser chamber and the evaporator 20 through the liquid line 22 and return pipe 23. As in Fig. 1, a trap 30 and thermostatically controlled solenoid valve 27, supplied with energy by a source of electrical energy 29, are disposed in the liquid and return lines, respectively. Thermostat 28 and indicator lamp 39 are shown as being in series with the valve actuating solenoid.

Regulating valves 18 and a charging valve 26 are also shown. Although not illustrated, it is to be understood that means are provided for drawing off CO_2 gas from the container and that the necessary blow-off valves are connected to the containers.

The particular disposition of the condensing chambers 45 within the containers is intended to obviate certain disadvantages inherent in condensers wherein the condensing surface is in contact with solid CO₂. As has been heretofore explained, the CO₂ is permitted to liquefy in the container after charging thereof by maintaining a pressure of about 100 pounds gage in the container. That portion of the CO₂ that has not liquefied will sink to the bottom of the container. Were the condensing surface in contact with the crystalline CO₂, the effective heat transfer area would be less than that in which only liquid CO₂ is in contact with the condensing surface. By placing the condensing chamber at a height somewhat above the bottom of the container, it will be in heat exchanging relation with only liquid CO₂ until the level of the liquid falls below the condenser and thereafter sufficient heat will be conducted through the container wall to condense gas in the condenser.

Still another advantage in spacing the condenser from the surface on which the solid CO₂ rests is that, when the container is being blown off, prior to recharging, there is a tendency for the liquid CO₂ to resolidify. This would result in sub-cooling of the secondary refrigerant in the condenser and a resulting drop in temperature in the refrigerator chamber.

The container is suitably insulated from the interior of cabinet 21, as indicated at 52 and 53, all heat transfer being effected through evaporator 20.

The refrigerating chamber or cabinet 21 corresponds in type and arrangement with the usual cabinets employed for the storage of ice cream. Suitable insulation 48 prevents, as far as possible, leakage of heat from the exterior of the cabinet, and removable covers 49 are placed over the several openings 51 provided for access to the cans of ice cream and to the CO₂ container. The evaporator 20 comprises coils 54 adjacent opposite side walls of the cabinet, each of said coils being welded to plates 55 to provide for large radiating surfaces. The coils are connected to vapor line 22 at the regulating valve and to liquid line 23 at trap 30.

By controlling the evaporator in the manner set forth, extremely close regulation of the cabinet temperature is possible. Tests have indicated that, if properly charged and replenished with CO₂, the evaporator will maintain a temperature varying less than 1° over a period of 24 hours even though the load fluctuations be relatively severe. Another advantage of the system is that the CO₂ is evaporated or used only as required to maintain the desired temperature in the refrigerator cabinet.

Another characteristic of the apparatus is uniform transfer of heat. Since no ice, oil or water are present in the system, and moving parts are unnecessary, the operation of the apparatus is unaffected by the usual factors common to other refrigeration systems. Furthermore, the CO₂ gas may be withdrawn for other purposes so that it is not entirely wasted.

Since ammonia and methyl chloride are readily responsive to temperature control and are generally in use as refrigerants because of their cheapness, it is obvious that they are preferred secondary refrigerants. It is intended, however, that the invention be adapted to the use of other refrigerants, not only secondary, but primary as well. It is also contemplated that modifications in the specific apparatus illustrated may be made

without departing from the invention. It is immaterial, for instance, whether the solenoid on the valve be energized to open or close the valve. If the refrigerating load is low, it may be advisable to energize the solenoid to open the valve, whereas when the load is relatively high and the valve is open over long periods, it is desirable to employ the solenoid to close the valve.

What is claimed is:—

1. A refrigeration system comprising a refrigerated chamber; a container having a primary refrigerant therein; a circuit having a secondary refrigerant therein, said circuit including a condensing chamber in heat exchanging relation with said container and an evaporator in said refrigerated chamber, said condensing chamber being of sufficient volume to contain substantially the entire charge of secondary refrigerant; means in said circuit for controlling flow of the secondary refrigerant from said evaporator to said condensing chamber; and means responsive to temperature in said refrigerated chamber for actuating said flow-controlling means.

2. A refrigeration system comprising a refrigerated chamber; a container having a primary refrigerant therein; a circuit having a secondary refrigerant therein, said circuit including a condensing chamber in heat exchanging relation with said container and an evaporator in heat exchanging relation with said refrigerated chamber, said condensing chamber being of volume sufficient to contain substantially the entire charge of secondary refrigerant; and means responsive to a predetermined temperature in said circuit to cause displacement of liquid refrigerant from said evaporator into said condensing chamber.

3. A refrigeration system comprising a refrigerated chamber; a container having carbon dioxide therein, said carbon dioxide having a temperature substantially lower than that to be maintained in the refrigerated chamber; a circuit having a secondary refrigerant therein, said secondary refrigerant being in heat exchanging relation with said container and said refrigerated chamber; a mixing valve; and means connecting said mixing valve with said container.

4. A refrigeration system comprising a refrigerated chamber; a container having a primary volatile refrigerant therein; pressure regulating means controlling the venting of primary refrigerant from said container and arranged to maintain in said container a pressure at which the primary refrigerant will liquefy; and a circuit having a secondary refrigerant therein, said circuit including a condensing chamber in heat exchanging relation with said container, an evaporator in said refrigerated chamber, said condensing chamber being disposed above the bottom of said container, a constantly open liquid connection between the lower portion of said condensing chamber and the lower portion of said evaporator and a vapor connection between the upper portion of said evaporator and said condensing chamber.

5. A refrigeration system comprising a refrigerated chamber; a container having a primary volatile refrigerant therein; pressure regulating means controlling the venting of primary refrigerant from said container and arranged to maintain in said container a pressure at which the primary refrigerant will liquefy; and a circuit having a secondary refrigerant therein, said circuit including a condensing chamber in heat exchanging relation with said container and an evaporator in said refrigerated chamber, said con-

densing chamber comprising a channel-shaped member secured to said container above the bottom thereof.

6. A refrigeration system comprising a refrigerated chamber; a container having a primary volatile refrigerant therein; pressure regulating means controlling the venting of primary refrigerant from said container and arranged to maintain in said container a pressure at which the primary refrigerant will liquefy; and a circuit having a secondary refrigerant therein, said circuit including a condensing chamber in heat exchanging relation with said container and an evaporator in said refrigerated chamber, said condensing chamber comprising a channel-shaped member secured to the interior of said container above the bottom thereof.

7. That method of utilizing carbon dioxide for refrigerating a chamber which comprises partly filling a container with solid carbon dioxide; so regulating the pressure in the container that the carbon dioxide will liquefy; circulating a volatile refrigerant in a closed circuit; evaporating the said refrigerant in a portion of the circuit in heat exchange relation with the chamber; and condensing said refrigerant in another portion of said circuit in heat exchange relation with the liquefied carbon dioxide.

8. That method of utilizing carbon dioxide for refrigerating a chamber which comprises partly filling a container with solid carbon dioxide; so regulating the pressure in the container that the carbon dioxide will liquefy; circulating a volatile refrigerant in a closed circuit; evaporating the said refrigerant in a portion of the circuit in heat exchange relation with the chamber; and condensing said refrigerant in another portion of said circuit in heat exchange relation with a portion of the container intermediate the top and bottom thereof. 5 10

9. The method of utilizing carbon dioxide for refrigerating a chamber which comprises partly filling a container with solid carbon dioxide; 15 maintaining a pressure of substantially one hundred pounds gage in the container whereby the carbon dioxide will be liquefied; circulating a volatile refrigerant in a closed circuit; evaporating the said refrigerant in a portion of the circuit in heat exchange relation with said chamber; condensing said refrigerant in another portion of the circuit in heat exchange relation with the liquefied carbon dioxide; and regulating the flow of vaporized refrigerant to said condensing portion to maintain a temperature of approximately 20 25 -25° F. therein.
